UNITED STATES PATENT OFFICE.

JOHN ELLERY SARGENT, OF MORGAN, KENTUCKY, ASSIGNOR OF ONE-HALF TO W. M. NORTHCUTT, OF MORGAN, KENTUCKY.

MEANS FOR SUPPLYING WATER.

Application filed December 19, 1923. Serial No. 681,535.

To all whom it may concern:

Be it known that I, JOHN ELLERY SARGENT, a citizen of the United States, and resident of Morgan, in the county of Pendleton and State of Kentucky, have invented 5 certain new and useful Improvements in Means for Supplying Water, of which the following is a full, clear, and exact description, reference being had to the accompanying drawings, forming a part of this specification.

My invention relates to means for supplying water of the type described in my pending application, filed September 19th, 15 1921, Serial No. 501,653, and has particular reference to improvements in the automatic valve construction set forth in said application.

The principal object of the present invention is to provide an automatic valve construction of improved efficiency.

Further objects of the invention will appear from the following detailed description thereof.

In the drawings:

Figure 1 is a plan of the tank and valve mechanism, part of the tank having been broken away to disclose the valve construction;

Figure 2 is a sectional view of the same; Figure 3 is a perspective of the valve stem and plunger construction together with the operating lever;

Figure 4 is a section of the frictional valve locking device;

Figure 5 is an end view of the valve;

Figure 6 is a perspective of certain of the valve elements disassembled.

The numeral 1 indicates a tank of any 40 suitable shape and construction and adapted to be submerged in the water in a cistern or other source of water supply. One of the end heads 2 of the tank is provided with a cylindrical valve housing 3, located in the 45 upper portion of the head. The inner end of the housing 3 forms a valve seat 4, and the outer end of said housing is provided with a diametric cross bar 5, which is provided with a central perforation or bearing 50 for a valve stem 6. Mounted on the stem 6 is a frame 7 provided with a solid end 8 and a spider end 9, the same being connected by bars 10. The frame 7 is adapted to bear in the cylindrical housing 3 and to 55 operate slidably therein. A rubber or other

resilient valve 11 is secured between the end 8 of the frame and the convex side of a plate 12, the several parts being secured in assembly on the stem by means of nuts 13 and 14, the stem being threaded through- 60 out a portion of its length as shown.

The outer end of the stem 6 of the valve beyond the spider 9 of the frame 7 is provided with two pairs of diametrically opposed notches 15 and 16, and flattened surfaces 17 between the pairs of notches. The cross bar 5 is provided with a bore 18 in which dogs 19 adapted to bear in either pair of notches 15 and 16, are inserted. Springs 20 secured by set screws 21 compress 70 the dogs against the valve stem 6. The outer end of the valve stem is provided with a collar or nut 22 to limit the possible inward movement of the valve.

The head 2 of the tank is provided with 75 lugs 23 in which the two arms 24 of valve operating mechanism are pivotally secured. The upper ends of the arms 24 are connected by a slotted head 25 arranged to receive loosely the stem 6 of the valve. Secured on the stem 6 beyond the head 25 is a nut or shoulder 26, the fingers 27 of the head 25 being arranged to bear against either of the nuts 14 or 26 for the purpose 80 of operating the valve.

Secured to the head 25 are arms 28, to the free ends of which a float 29 is pivotally connected.

The head 2 of the tank is provided with 85 an inlet 30 through which air pressure is maintained in the tank for forcing the water therein outwardly through the outlet 31, whence it is supplied to the various points of consumption.

A strainer 32 is secured to the intake end 90 of the valve housing 3 to prevent impurities from entering the tank.

The operation of the mechanism is as follows:

Assuming the tank 1 to be full, the float 100 29 is in upper position where the fingers 27 will bear against the nut 14, forcing the valve against the seat 4. Air pressure introduced in the tank through the inlet 30 forces the water in the tank through 31 to 105 the various points of consumption, as required. As the water level in the tank goes down the float 29 drops and the fingers 27 are withdrawn from the nut 14; as however, there is a considerable distance before 110

the fingers bear against the nut 26, the valve is not affected by the fingers until the float has dropped to a predetermined point, that is where the tank is approximately 5 empty. Until this point is reached, the valve is held in closed position, partly by the air pressure in the tank and partly by the engagement by the dogs 19 in the notches 16 of the stem.

10 When the predetermined minimum level is reached however, the fingers 27 engage the nut 26 and force the stem 6 inwardly, the surfaces 17 of said stem sliding between the dogs until the valve is fully opened, when 15 the dogs engage in the notches 15. When the valve is thus opened, the air pressure in the tank is released through the valve and water from the cistern or other source of supply flows inwardly, raising the float 29 20 until the fingers 27, bearing against the nut 14, again close the valve against the friction of the dogs 19.

By this construction I have provided an 25 automatic valve which is highly efficient in operation, the frame 7 providing an extended bearing surface in the housing 3, which so centers the valve stem that the operation is at all times smooth and accurate.

As an incidental advantage of my valve 30 construction it will be noted that the release of the air from the tank when the valve is opened is calculated thoroughly to aerate the water in the cistern or other source of supply, thereby keeping it entirely fresh and 35 sanitary.

Having thus fully described my invention what I claim as new, and desire to secure by Letters Patent, is:-

1. In a device of the character specified, 40 valve mechanism comprising a housing, one end of said housing being arranged to form a valve seat, a valve stem, a valve secured to said stem, a bearing frame secured to said stem and arranged to bear slidably inside said housing, a float, means for frictionally holding said valve stem in either 45 open or closed position, and means whereby said float is arranged to operate said valve

against said friction when liquid in the tank reaches predetermined levels. 50

2. In a device of the character specified, valve mechanism comprising a housing, one end of said housing being arranged to form a valve seat, a bearing in the other end of said housing, a valve stem arranged to reciprocate in said bearing, a valve secured to said stem, a bearing frame secured to said stem and arranged to bear slidably inside said housing, a float, means for frictionally holding said valve stem in either open or closed position, and means whereby said float is arranged to operate said valve against said friction when liquid in the tank reaches predetermined levels. 55

3. In a device of the character specified, valve mechanism comprising a housing, one end of said housing being arranged to form a valve seat, a valve stem, a flexible valve secured to said stem, a bearing frame secured to said stem and arranged to bear slidably 60 inside said housing, a valve plate having a convex surface arranged to bear against said valve to cause it to seat, a float, means for frictionally holding said valve stem in either open or closed position, and means whereby 65 said float is arranged to operate said valve against said friction when liquid in the tank reaches predetermined levels. 70

4. In a device of the character specified, valve mechanism comprising a housing, one end of said housing being arranged to form a valve seat, a bearing in the other end of said housing, a valve stem arranged to reciprocate in said bearing, a flexible valve secured to said stem, a bearing frame secured to said stem and arranged to bear slidably 75 inside said housing, a valve plate having a convex surface arranged to bear against said valve to cause it to seat, a float, means for frictionally holding said valve stem in either open or closed position, and means whereby 80 said float is arranged to operate said valve against said friction when liquid in the tank reaches predetermined levels. 85

JOHN ELLERY SARGENT.
